CONTROL SYSTEM

Alonzo F. Kenyon, Wilkinsburg, Pa., assignor to
Westinghouse Electric & Manufacturing Com-
pany, East Pittsburgh, Pa., a corporation of
Pennsylvania

Application July 25, 1939, Serial No. 286,338

4 Claims. (Cl. 80—32)

My invention relates, generally, to control systems, and, more particularly, to systems for controlling the tension on strip material as it is being passed through a rolling mill.

In the operation of steel strip rolling mills, it is desirable that back and front tensions be applied to the strip as it enters and leaves the working rolls. For best results in the rolling operation, the front and back tensions should be much greater than can be applied through the unwinding and winding reels. It has become the practice, therefore, to provide tensioning devices between the unwinding reel and the working rolls and between the working rolls and the winding reel which will function to provide much higher front and back tensions at the working rolls than the winding and unwinding reel tensions. One such tensioning device for providing front tension on the strip as it leaves the roll stand has been in the form of a pulling device comprising a pair of driven rolls over which a partial wrap of the strip is taken in passing from the roll stand to the winding reel. These two rolls provide the front tension on the strip while the winding tension is independent of the front tension.

Heretofore, the rolls of such pulling devices have been geared together and driven by a single motor. This method of operation has been found unsatisfactory for the reason that small differences in the diameters of the rolls of the pulling device cause slippage and buckling of the strip on the rolls and sometimes cause one of the rolls to carry all of the pulling load.

The objects of my invention are to provide an individual motor drive and control system therefore for strip pulling devices which shall function to properly distribute the pulling load between the rolls of the pulling devices, which shall be simple and efficient in operation and which shall be inexpensive to manufacture, install, operate and maintain.

These and other objects and advantages of the invention will be apparent from the following detailed description taken in connection with the accompanying drawing in which the single figure is a diagrammatic view of a single stand strip rolling mill embodying the principal features of my invention.

As the strip 10 leaves the working roll stand 12, it passes in a partial wrap around each of the pair of rolls of a pulling device 14 and is wound upon a reel 16. The upper and lower rolls 18 and 20 of the pulling device 14 are driven by the motors 22 and 24, respectively, to subject the strip to

tension as it leaves the roll stand 12. The motors 22 and 24 are connected in series circuit relation and motor 22 is made to apply a greater tension to the strip than the motor 24 either by the proper adjustment of the relative excitations of the motors, or by making motor 22 of a greater power rating than motor 24.

The working roll stand 12 and the winding reel 16 are driven by the motors 26 and 28, respectively, and suitable controllers 30, 32, 34 and 36 are provided for separately and collectively controlling the motors and the potential of the generator 38, which is the source of power for the motors, during the inching operations and the normal running of the mill.

Considering the system more in detail, the polarity of the potential supplied to the motors by the generator 38 is selectively determined by the reversing switch 40 which, upon the selective energization of the relays 42 and 44, supplies the desired polarity of energizing potential for the field winding 46 of the generator 38 from the source of direct current power, represented by the conductors A—B, over the conductors 48 and 50. The direction of rotation of the motors 22, 24, 26 and 28 can thus be controlled by the controlling of the polarity of the generator 38. The value of the output potential of the generator 38 may be controlled by the field rheostat 52 so that any desired potential may be supplied to the motors 22, 24, 26 and 28 to operate the mill at any required speed for inching, threading, or running of the mill.

The armature of the motor 26 may be connected to the main power conductors X—Y by the switch 54 through a circuit which extends from the conductor X through conductor 56, contact element 58 of the switch 54, conductor 60, the armature of the motor 26, conductor 62, contact element 64 and the conductor 66 to the conductor Y.

A similar circuit for energizing the armatures of the motors 22 and 24 in series circuit relation is controlled by the switch 68 and extends from the conductor X through the conductor 70, contact element 72 of the switch 68, conductor 74, the armature of the motor 24, conductor 76, the armature of the motor 22, conductor 78, contact element 80 of the switch 68 and conductor 82 to the conductor Y. A resistor 84 may be connected in shunting relation with the armatures of the motors 22 and 24 by a switch 86 through a circuit which extends from the conductor 74 through the conductor 88, contact element 90 of

the switch 86, the resistor 84, conductor 92, contact element 94 of the switch 86 and the conductor 96 to the conductor 78. The resistor 84 may be apportioned as a shunting resistance for the armatures of the motors 22 and 24 by a conductor 98 extending between the conductor 76 which connects the armatures of the motors 22 and 24 and an adjustable tap 99 on the resistor 84.

A switch 100 is provided to connect the armature of the motor 28 to the power conductors X-Y through a circuit which extends from the conductor X through the conductor 102, the contact element 104 of the switch 100, the armature of the motor 28, conductor 106, contact element 108 of switch 100 and conductor 110 to the conductor Y.

The controller 30 is provided for controlling the polarity of the generator 38 and the energization of the armature of the motor 26 for threading the strip through the rolls of the mill stand 12 or inching the rolls of the mill stand in a forward or reverse direction. To operate the motor 26 in the forward direction, the movable contact elements of the controller 30 are actuated to the left-hand position which causes the contact element 112 to complete an energizing circuit for the relay 42 of the reversing switch 40. This circuit extends from the conductor B through the conductor 114, conductor 116, contact element 112, conductor 118, the winding of the relay 42 and conductor 48 to the conductor A. At the same time, the contact element 120 of the controller 30 completes a circuit for the switch 54 which extends from the conductor A through the conductor 122, conductors 123 and 124, contact element 120, conductor 126, conductor 128, the winding of switch 54 and conductor 114 to the conductor B. Thus, by operating the movable contact elements of the controller 30 to the left-hand position, the armature of the motor 26 is connected to the power conductors X-Y and the relay 42 energizes the field winding 46 of the generator 38 with such a polarity as to cause the generator 38 to energize the conductors X-Y with a polarity which will cause the forward rotation of the motor 26. Upon actuation of the movable contact elements of the controller 30 to the right-hand position, the motor 26 will be energized with such a polarity as to cause it to rotate in the reverse direction. When the movable contact elements of the controller 30 are moved to the right-hand position, the contact element 112 completes a circuit for the relay 44 of the reversing switch 40 which extends from the conductor A through the conductors 122 and 123, contact element 112, conductor 130, the winding of the relay 44 and conductors 132 and 50 to the conductor B. The contact element 120 completes a circuit for the switch 54 which extends from the conductor A through the conductor 122, contact element 120, conductors 124, 126, and 128, the winding of the switch 54 and the conductor 114 to the conductor B.

Control of the motors 22 and 24 for threading the strip through the pulling device 14 and for inching the pulling device is provided by the controller 34. When the controller 34 is actuated to the left-hand position, the contact element 136 thereof completes a circuit for the relay 42 which extends from the conductor B through the conductors 138 and 140, the contact element 136, conductors 142 and 118, the winding of the relay 42 and the conductor 48 to the conductor A. The contact element 144 of the

controller 34 completes a circuit for the switch 68 which extends from the conductor A through the conductor 146, contact element 144, conductor 148, the winding of switch 68 and conductor 138 to the conductor B. The contact element 150 of this controller completes a circuit for the switch 86 which extends from the conductor B through conductors 152 and 154, contact element 150, conductors 156 and 158, the winding of the switch 86, and the conductor 160 to the conductor A. The polarity of the generator 38 will thus be such as to provide forward rotation of the motors 22 and 24 and the resistor 84 will be connected in shunting relation with the armatures of these motors to divide the voltage between the armatures to insure rotation of the motors 22 and 24. This shunting resistor 84 or some similar device is necessary during the threading or inching operations when there is not good contact between the strip 14 and the tensioning rolls 18 and 20 to assure rotation of both motors. During such time as these rolls are not tied together by the firm contact of the strip 14 with each of them, the motor having the least load may start and come up to speed, taking all the voltage of the series circuit and preventing the other motor from starting. With the resistor 84 connected in shunting relation with the armatures of the motors 22 and 24 and the parts of the resistor divided between the motors by the conductor 98 and the tap 99, the potential supply across the conductors X-Y will be divided between the motors 22 and 24 in accordance with the relative resistance of the parts of the resistor 84 on each side of the tap 99. Thus the resistor 84 may be proportioned between the motors 22 and 24 to insure that both will always start during the threading and inching operations.

Upon actuation of the controller 34 to the right-hand position, the contact element 136 will complete a circuit for the relay 44 of the reversing switch 40 which extends from the conductor A through the conductors 160 and 162, contact element 136, conductors 164, 130, the winding of relay 44 and the conductors 132 and 50 to the conductor B. Simultaneously, the contact element 144 will complete a circuit for the switch 68 which extends from the conductor A through the conductors 146 and 166, contact element 144, conductors 168 and 148, the winding of switch 68 and conductor 138 to the conductor B. The contact element 150 will complete a circuit for the switch 86 which extends from the conductor B to the conductor 152, contact element 150, conductor 158, the winding of switch 86, and conductor 160 to the conductor A. Thus reverse rotation of the motors 22 and 24 for inching purposes is provided.

The controller 36 may be actuated to control the forward and reverse rotation of the reel motor 28. The actuation of the controller 36 to the left-hand position will cause the contact element 170 to close an energizing circuit for the relay 42 which extends from the conductor B through the conductors 172 and 174, contact element 170, conductors 176 and 118, the winding of relay 42 and the conductor 48 to the conductor A.

The contact element 178 will complete a circuit for the switch 100 which extends from the conductor A through the conductors 180, 182, and 184, contact element 178, conductors 186, 188 and 190, the winding of switch 100 and conductor 172 to the conductor B. Energization

of the reel motor 28 in the reverse direction is provided by actuating the controller 36 to the right-hand position to cause the contact element 170 to complete an energizing circuit for the relay 44 of the reversing switch 40 which extends from the conductor A through the conductor 180, contact element 170, conductors 192 and 130, the winding of relay 44 and conductors 132 and 50 to the conductor B. The contact element 170 meanwhile completes a circuit for the switch 100 which extends from the conductor A through conductors 188 and 182, contact element 178, conductors 188 and 190, the winding of relay 100 and conductor 172 to the conductor B.

In threading the strip 10 through the mill and performing inching operations, the output potential of the generator 38 may be made much lower than the normal running potential so that the motors 22, 24, 26 and 28 will run at a much lower speed.

When the strip 10 has been threaded through the roll stand 12 and the pulling device 14 and started on the reel 16, the drive motors for the roll stand 12, the pulling device 14 and the reel 16 may be controlled simultaneously to run in the forward direction by the controller 32. The actuation of the controller 32 to the left-hand position will energize the relay 42 of the reversing switch 40 through a circuit which extends from the conductor B through the conductor 196, contact element 194, conductors 198 and 118, the winding of the relay 42 and the conductor 48 to the conductor A. At the same time, the contact element 200 will close an energizing circuit for the switch 54 to energize the armature of the motor 26 which extends from the conductor A through the conductor 262, contact element 200, conductor 128, the winding of the switch 54 and conductor 114 to the conductor B. The contact element 204 will close an energizing circuit for the switch 68 to connect the motors 22 and 24 in series circuit relation to be energized by the generator 38 in a circuit which extends from the conductor A through the conductors 202 and 206, contact element 204, conductors 208, 168 and 143, the winding of switch 68 and the conductor 138 to the conductor B. The armature of the reel motor 28 will also be energized by the energization of its control switch 100 through a circuit which is completed by the contact element 210 and which extends from the conductor A through the conductors 202 and 212, contact element 210, conductor 190, the winding of switch 100 and conductor 172 to conductor B.

Thus the armatures of the motors 22, 24, 26 and 28 will be connected to the power conductors X-Y to be energized by the generator 38, the generator 38 will be excited with such a polarity as to provide energizing power for the motors 22, 24, 26 and 28 which will cause them to rotate in the forward direction, and the rheostat 52 may be manipulated to increase the output potential of the generator 38 and thus increase the speed of the motors to bring the mill up to normal running speed.

The strip 10 will be wound upon the reel 16 under a light tension, the amount of the winding tension being controlled by any suitable means which will control the torque of the motor 28. The front tension applied to the strip 10 as it leaves the roll stand 12, will be much greater than the winding tension and it will be equal to the sum of the tension applied to the strip 75

by the tensioning roll 18 driven by the motor 22, the tension applied to the strip by the tensioning roll 20 driven by the motor 24 and the winding tension. It will be apparent therefore, that the pressure of the strip on the tensioning roll 18 will be greater than on the tensioning roll 20. The roll 18 will, therefore, have a greater traction on the strip 10 than the tensioning roll 20 and it will be possible to apply a much greater tension to the strip through the tensioning roll 18 than through the tensioning roll 20. In order to operate the tensioning device most efficiently, therefore, a greater amount of the tension should be supplied by the motor 22 through the tensioning roll 18 than by the motor 24 through the tensioning roll 20.

In order to provide this greater power output of the motor 22, alternative methods of operation are possible. The motors 22 and 24 may be made of the same horsepower rating and the motor 24 provided with smaller excitation than the motor 22. Thus, assuming that the power potential across the conductors X-Y is 600 volts and the motors 22 and 24 are 400 volt motors, if the motor 24 is excited at half its normal excitation, it will be running as a 200 volt machine, motor 22 will be running as a 400 volt machine and the motor 22 will be carrying twice as much load as the motor 24.

A more efficient method of operation would be to choose the relative sizes of the tensioning roll drive motors approximately proportional to the loads to be carried by them, as determined by the traction of the strip 10 upon their associated tensioning rolls. Thus, if it is desired that the motor 22 carry three-fourths of the tensioning load and the motor 24 carry only one-fourth of the tensioning load, the motors 22 and 24 may be made of substantially the same current rating but of a voltage rating in the proportion of three to one. Thus, if the motor 22 is a 450 volt motor and the motor 24 is a 150 volt motor, since they have the same armature current, being connected in series circuit, the total tensioning power will be divided between them in the proportion of 450 to 150, or three to one.

If, now, with motors 22 and 24 having substantially the same current ratings and voltage ratings in the proportion of three to one installed on a particular mill, it is desired to provide a different proportioning of the load between the motors, their excitations may be varied by means of the rheostats indicated in circuit with their field windings to vary the potential distribution and, therefore, the power distribution between them.

In such a strip rolling mill as is described herein, it is common practice to also provide a pulling device on the feeding side of the mill stand 12 between the roll stand 12 and an unwinding reel to provide back tension on the strip 10 as it enters the roll stand 12. Such pulling devices are similar to the pulling device 14 with braking generators driven by the tensioning rolls to provide a braking effect, and, therefore, a back tension on the strip 10, and the unwinding reel is also made to drive a braking generator to provide unwinding reel tension and to maintain back tension on the pulling device. It is to be understood that the invention herein described may be applied to such a mill to provide the most efficient operation of the pulling device which provides back tension on the strip and

that the control system described in detail herein may be extended and applied to the braking generators which are connected to the back pulling device and the unwinding reel by operating the reel 16 as an unwinding reel and operating the motors 22, 24 and 28 as braking generators to provide back tension as the strip 10 passes from the reel 16 to the roll stand 12. It is to be further understood that such pulling or tensioning devices as those described herein may be used to provide both front and back tension on a strip as it is passed through a rolling mill in the manner described in the Hudson Patent No. 2,054,819, and that the pulling device may be operated in either direction by causing the motors connected to the tensioning rollers to act as either motors or generators depending upon the direction of travel of the strip, as fully explained in the copending application of G. P. Lessmann et al. Serial No. 210,194, filed May 26, 1938, now Patent No. 2,195,009, issued March 26, 1940.

The provision of the resistor 84 to be connected in shunting relation with the armatures of the motors 22 and 24 to insure rotation of the motors 22 and 24 during threading and inching operations is merely a convenient electrical system for performing this function and other means for performing this function may be provided. As an example, the motors 22 and 24 may be mechanically connected together by a light friction belt so that if there is a tendency of one to rotate and the other to stand still due to unequal distribution of load between them, they will both be made to rotate by the mechanical connection. Such a connection would be only a friction connection in which there may be some slippage to permit slight differences of speeds of rotation of the motors due to slight differences in the diameters of the tensioning rolls to which they are connected. Such a mechanical connection may also be provided connecting the tensioning rolls 18 and 20 instead of the motors 22 and 24.

It will be apparent that I have provided a tension control system for a strip rolling mill which shall function to properly distribute the pulling load between the rolls of the pulling devices of the mill which shall be simple and efficient in operation and which shall be inexpensive to manufacture, install and repair.

In compliance with the requirements of the patent statutes, I have shown and described herein the preferred embodiments of my invention. It is to be understood, however, that the invention is not limited to the precise construc-

tions shown and described but is capable of modification by one skilled in the art, the embodiments herein shown and described being merely illustrative of the principles of my invention.

I claim as my invention:

1. In a strip tension control system, in combination, a pair of spaced rolls over which the strip passes in frictional engagement, a drive motor for each of the said rolls, circuit means energizing the armatures of said motors in series circuit relation, and means for varying the relative values of the excitations of said motors whereby one of said motors will subject the strip to a greater tension through its associated roll than the other motor, voltage dividing means for providing a predetermined energization of each of the armatures of said motors, and means for rendering said voltage dividing means effective.

2. In a strip tension control system, in combination, a pair of spaced rolls over which a strip which is being acted upon by a work device passes in frictional engagement, a dynamo-electric machine mechanically connected with each of said rolls, circuit means connecting the armatures of said dynamo-electric machines in series circuit relation, means for varying the relative values of the excitations of said dynamo-electric machines to thereby cause different tension forces to be transmitted between the strip and the two dynamo-electric machines through their associated rolls, and means for ensuring rotation of both of the rolls during inching operations of the work device.

3. In a strip tension control system for a strip rolling mill, in combination, a pair of spaced rolls over which the strip passes in frictional engagement, a motor connected in driving relation with each of the rolls, circuit means connecting the armatures of said motors in series circuit relation, voltage dividing means for providing a predetermined energization of each of the armatures of said motors, and means for rendering said voltage dividing means effective during the inching operations of the mill.

4. In a strip tension control system for a strip rolling mill, in combination, a pair of spaced rolls over which the strip passes in frictional engagement, a motor connected in driving relation with each of the rolls, circuit means connecting the armatures of said motors in series circuit relation, and means for ensuring rotation of both of the rolls during the inching operations of the mill, when the strip is not in frictional engagement with both of the rolls.

ALONZO F. KENYON.
